US00D970553S

(12) **United States Design Patent** (10) **Patent No.:** **US D970,553 S**
(45) **Date of Patent:** **** Nov. 22, 2022**

(54) **PART OF BALL INFLATOR**

- (71) Applicant: **Wan-Sheng Yu**, Taichung (TW)
(72) Inventor: **Wan-Sheng Yu**, Taichung (TW)
(**) Term: **15 Years**
(21) Appl. No.: **29/711,003**
(22) Filed: **Oct. 28, 2019**
(51) LOC (13) Cl. **15-07**
(52) U.S. Cl. **USPC D15/7**
(58) **Field of Classification Search**
USPC D23/231, 232; D15/7, 8; D8/303, 306
CPC F04B 33/00; F04B 33/005; F04B 39/005;
F04B 5/02; F04B 25/005

(57) **CLAIM**

The ornamental design for a part of ball inflator, as shown and described.

DESCRIPTION

FIG. 1 is a perspective view of a part of ball inflator showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

1 Claim, 5 Drawing Sheets
